Delmer S. Fahrney, United States Navy

Application October 7, 1943, Serial No. 505,320

7 Claims. (Cl. 244—3)

(Granted under the act of March 3, 1883, as amended April 30, 1928; 370 O. G. 757)

1

The present invention relates to a glider adapted to be towed or carried by an airplane, the fuselage being formed of any suitable light-weight material and of any desired configuration, the wing and control surfaces being of conventional design. The present application is a continuation in part of pending application Serial Number 407,140, filed August 16, 1941, now matured into Patent 2,399,215.

It is an object of the present invention to provide the fuselage with compartments that house radio control equipment, television, servo-motors, batteries, relays, stabilizers, generators, auxiliary fuel tank, bomb, torpedo, flare and smoke screen material.

A still further object of the present invention is the provision of a tow cable and means for guiding the glider below the line of tow.

A still further object of the present invention is the provision of means responsive to any change in the angle of tow.

A still further object of the present invention is the provision for pilotless towing of a glider through use of stabilizers and servo mechanism to actuate the control surfaces of the glider automatically.

A still further object of the present invention is the provision of detachable means on the fuselage operable by release mechanism controlled from the towing airplane.

A still further object of the present invention is the provision of releasable means connecting the airplane and glider, also controlled from the towing airplane.

A still further object of the present invention is the provision of means controlled from the towing airplane for releasing material from some of the compartments in the fuselage of the glider.

A still further object of the present invention is the provision of means in some of the compartments of a glider responsive to directional apparatus for controlling the glider when released from a tow line.

Other objects and advantages of the present invention will be more apparent from the following description and claims.

Referring now to the accompanying drawings which are made a part hereof, and on which similar reference characters indicate similar parts throughout the several views.

Figure 1 is a side elevational view of a glider fuselage and detachable wing. The servo-motor, stabilizer, battery and bomb compartments being shown in dotted lines in the fuselage, a tow line and cables being shown fragmentarily and con-

2

nected to conventionally illustrated release means.

Figure 2 is a view similar to Figure 1, the wing being provided with adjustable diving flaps, the glider fuselage with a television or radio compartment shown in dotted lines and with a tow line and cables shown fragmentarily and connected to conventionally illustrated release means.

Figure 3 is a view similar to Figure 1, the wing in the drawing being fixedly secured to the fuselage, the fuselage provided with a fuel compartment shown in dotted lines and a fuel supply conduit connected to a valve in said compartment, the tow line, cables and fuel supply conduit being shown fragmentarily and connected to release means shown conventionally.

Figure 4 is a view similar to Figure 3, the fuselage being provided with a compartment and a hinged door, a bomb or torpedo in said compartment, the bomb or torpedo being shown in dotted lines, the tow line and cables being shown fragmentarily and connected to release means shown conventionally.

Figure 5 is a side elevational view of a glider fuselage, the fuselage provided with radio, television, relays, generators, servo-motors and bomb compartments shown in dotted lines, a tow line connected to release means shown conventionally in the nose of the fuselage, a feeler and a guiding arm connected in the nose of the fuselage, and means on the tow cable for holding the guiding arm, the tow cable being shown fragmentarily and the fuselage broken.

Figure 6 is a side elevational view of a modified form of the present invention in which the glider is secured to release means on the airplane, the fuselage of the glider being provided with compartments for extra fuel supply shown in dotted lines; and a fuel supply conduit connected to a valve in said compartment as shown, with means for opening the valve and means for releasing the conduit being shown conventionally as in Fig. 3.

Figure 7 is a plan view of a type of hinge for connecting a plate and a wing to the fuselage and illustrating the connecting pin and solenoid.

Referring now to the drawings, the fuselage or body 8 of the glider may be made of any suitable light-weight material, such as metal, plastic or the like, the fuselage being formed in any desired configuration. As illustrated in the drawings, the fuselage 8 is provided with a plurality of compartments, the numeral 9 representing the electric or hydraulic servo and stabilizer com-

partment, 10 the battery compartment and 11 the compartment for high explosives.

In Figure 1, the fuselage 8 is provided with a wing 12 that is detachably secured to the body in the following manner. On the fuselage 8 are mounted plate members 14 that are bolted or otherwise secured to the fuselage, the members being provided with spaced knuckles 15. On the wing 12 are mounted plate members 16 that are bolted or otherwise secured to the wing, the members being provided with knuckles 17 that engage the knuckles 15. The plates are detachably connected by a pin 18 that passes through the sets of knuckles. One end of the pin 18 is connected to means releasably secured between the wing and the fuselage and adapted to uncouple the plates and, in the present showing I have illustrated one form of uncoupling means in the form of a solenoid 19 for operating the pin 18. Solenoids being of well-known types and well known in the art, I have not shown them in detail. I would, at this point, have it distinctly understood that although I have shown a solenoid, I do not wish to limit myself to same, as other types of release means may be employed. A tow line 20 connects the glider to an airplane (not shown), one end of the tow line being provided with a clevis 21 operatively secured to a plate support 22 that carries knuckles 23 and a solenoid 19. Secured to the fuselage 8 in any suitable manner is a plate 24 having a knuckle 25 that engages knuckles 23, the plates being held in detachable engagement by pin 18, one end of the pin being connected to solenoid 19. The tow line 20 carries a plurality of electric cables 26 that connect solenoids 19 to a source of electrical energy in an airplane (not shown).

In Figure 2 of the drawings, the wing 12 is shown as being fixedly secured to the body 8 and it is provided with adjustable diving flaps 27 and 28 which can be set automatically on release of glider. In the nose of the fuselage 8, in compartment 9, is housed an electric or hydraulic servo and stabilizer, in compartment 10 batteries, and in compartment 38 television or radio equipment, all of the equipment being well known in the art, it is not shown in detail. The fuselage is provided with the tow line release mechanism illustrated in Figure 1.

In Figure 3, in the nose of the fuselage 8 in compartment 9 is an electric or hydraulic servo and stabilizer and in compartment 10 a battery. Within the fuselage 8 is a fuel compartment 31 having an outlet valve 32 equipped with a coupling nipple 33 that engages the end of a fuel hose 34, the fuel hose being carried by the tow line 20. The fuselage 8 carries a plate 35 that may be detachably secured to the fuselage, the plate carrying a pair of solenoids 36 and 37. Connected to the solenoids 36 and 37 are electric cables 26 that are carried by the tow line 20. Pin 38 of solenoid 36 engages the valve 32 while pin 39 of solenoid 37 engages the coupling nipple 33. The tow line release mechanism is the same as illustrated in Figure 1.

In Figure 4 of the drawings, the compartment 40 is adapted to house a bomb or, as illustrated, torpedo 41 shown in dotted lines. The compartment 40 is provided with a trap door 42 that is provided with a catch lug 43. The plate support 22 in this view is somewhat longer and allows for the mounting of an additional solenoid 44 having an engaging pin 45. The pin 45 engages the catch lug 43 and holds the trap door

42 in locked position. Although I have shown in Figure 4 an aerial torpedo 41 in compartment 40, I would have it distinctly understood that this compartment may be utilized for housing flare or smoke screen material.

In Figure 5, I have shown the solenoid 19 mounted in the nose of the fuselage 8. The tow line 20 is provided with a ring 60 for a purpose to be later described. This tow line is connected by means of a clevis or other link means 21 to a contact means held by a pin actuated by the solenoid 19 in a manner similar to the connections previously defined. Within the fuselage 8 there is provided an electrical relay box 61 and mounted in the box 61 in any suitable manner for movement and contact therein is one end 62 of a feeler arm 63, the opposite end portion 64 being held in engagement with a ring 60. The electrical relay box 61 is connected by suitable electric conduits to the compartment 9 that houses a stabilizer mechanism and gyros. When the glider is towed the relay in the box 61 is set to operate the stabilizer mechanism to move the glider control surfaces in response to any deviation in the angle of the feeler arm 63 from that for which it is set, to bring the glider back into a relative position with respect to the airplane to return the feeler arm again to its normal angular position. The solenoid 19, the stabilizers and gyros are connected to the radio compartment 29 by suitable conduits (not shown) so that when the glider is released by operation of the solenoid 19 it simultaneously turns on gyro stabilization and radio, television and other equipment as may be desired. Electrical energy for operating the various devices may be supplied by a fan-driven generator or a gasoline-engine generator housed in compartment 65. Within the fuselage 8 are mounted small electric motors 66 that are connected to compartment 9 by suitable electrical conduits (not shown). Television or target seeking mechanism is housed in compartment 30 and it is connected by suitable conduits (not shown) to the radio compartment 29. The battery 43 serves to supply current to some of the devices through conduits (not shown) that connect the battery with some of the compartments.

In Figure 6, I have illustrated a modified form of my invention in which the glider is detachably mounted on an airplane. The fuselage 8' is provided with a plurality of compartments previously described and, therefore, no further description is deemed necessary. To the wings 12' are secured struts 46 having a knuckle 47 that engages knuckles 48. Mounted on the fuselage 49 is a solenoid 50 having a pin 51 that engages the knuckles 47 and 48. On the vertical stabilizer 52 there is mounted a plate 53 that is provided with knuckles 54 that are engaged by knuckle 55 carried by the fuselage 8'. The plate 53 also carries a solenoid 56 having a pin 57 that engages the knuckles 54 and 55. An electric conduit 58 connects the solenoids with a source of electrical energy within the fuselage 49. A fuel tank 31 is connected, by means similar to those shown in Fig. 3, to the fuel reservoirs in the airplane fuselage 49 for refueling them from tank 31.

In the use of the glider illustrated in Figure 1, the glider is towed to a target at which point the pilot of the airplane towing the glider presses a button or switch making contact with a source of electrical energy, the electrical energy passing through the conduits 26 to the solenoids 19, thus energizing the solenoids, withdrawing the pins from the knuckles, thus releasing the wing, the

tow line and the electrical cables. Upon release of the wing, electrical cables and tow line, the fuselage carrying the bomb falls free onto the target.

In the glider illustrated in Figure 2, the glider is towed to an objective, the glider in this view having the wing fixedly secured to the fuselage. The diving flaps 27 and 28 are set at a predetermined angle. Through energization of a solenoid 19 from the source of electrical energy in the towing airplane the tow cable and electrical cables are released from the fuselage. The equipment 30 (television or radio detectors) directs the released glider bomb to its objective, the radio, servo-motors, stabilizers and television being supplied with current from the battery source. The control pilot in the tow plane through the radio equipment actuating appropriate relays, actuates servo mechanism in the glider bomber directing it toward the target as indicated by radio or television equipment until the glider bomber strikes its objective.

In the use of the glider illustrated in Figure 3, the glider serves as an auxiliary fuel tank. The fuel is released from the tank 31 by the energization of the solenoid 36 withdrawing the pin 38, the gasoline passing from the tank or compartment 31 through the fuel hose 34 to the fuel tank in the towing airplane. When the compartment 31 is empty the glider can be released or towed back to base station. To release, the pilot presses a switch connecting the source of electrical energy with the solenoids 19 and 37 thus releasing from the glider the tow line 20, the electric conduits 26 and the fuel hose 34, the glider will glide to a landing on field or water through the medium of the operation of glider controls by servo mechanism and stabilizers.

In the use of the glider illustrated in Figure 4, the compartment 40 being loaded with a bomb or torpedo, the glider towed to an objective at which point the pilot of the towing airplane throws a switch, the electric current passing through the cable 26 energizes the solenoid withdrawing the pin from the trap door catch lug 43, 45 the door opening and releasing the bomb or torpedo simultaneously with the energization of solenoid 44. The glider can then be returned to base and released by energization of solenoid 19. The glider is freed from the tow line 20 and the electric cables 26 and glides to a landing through actuation of control surfaces by servo and stabilizers energized by a battery.

In the use of the glider illustrated in Figure 5, the automatic tow operates in the following manner. The glider is towed below the towing airplane, the feeler arm is held in engagement with, and at an angle to the tow line by ring 60. During the towing of the glider any change in the angle of tow of the glider, either to the right, left, up or down is immediately transferred to the relay 61 that transfers the change to the small motors 66, that changes the follow-up ratio on the gyro-stabilizers, the stabilizers causing the glider to assume proper tow position. Electrical energy is supplied by the wind-driven generator or gasoline-motor generator 65. The solenoid 19 and the gyro-stabilizers being connected to the radio compartment, radio control directed signals will release the tow line, the glider being stabilized for level flight. At this point the television or target seeking device is automatically turned on and the glider will then react to radio signals or answer automatically, directions given by the target seeking apparatus.

The modification of my invention illustrated in Figure 6, the glider being detachably secured to the airplane is carried to the desired objective at which point energization of the solenoids 50 and 56, the pins 51 and 57 are withdrawn from the knuckles, releasing the glider. This glider is primarily designed to carry additional fuel in its fuselage to increase materially the range of the airplane supporting it, the glider's wing being of ample proportions to lift the additional weight.

Other modifications and changes in the proportions and arrangement of the parts constituting the invention may be made by those skilled in the art without departing from the nature and scope of the invention, as defined in the appended claims.

The invention described herein may be manufactured and/or used by or for the Government of the United States of America for governmental purposes without the payment of any royalties therein or therefor.

What I claim is:

1. In combination with an airplane a glider having a fuselage and wing, release means connecting said wing to said fuselage, a tow line connecting said fuselage to said airplane, one end of said tow line having release engaging means, release means carried by said fuselage and adapted to receive said tow line release engaging means, means carried by said tow line connecting said release means for said wing and tow line release engaging means with means in said airplane, and means in said glider for directing said glider after release of said wing and tow line.

2. In combination with an airplane a glider, means connecting said glider to said airplane, contact means carried by said glider in contact with said connecting means, means carried by said connecting means for holding said contact means in contact with said connecting means, and means on said connecting means responsive to remote control signals for releasing said connecting means and automatically stabilizing said glider for level flight.

3. In combination with an airplane a glider, means connecting said glider to said airplane, contact means carried by said glider in contact with said connecting means, means carried by said connecting means for holding said contact means in contact with said connecting means, means in said glider responsive to any angular change of said connecting means with respect to said glider, surface control means in said glider for correcting said angular change of said connecting means operated by said responsive means, and means in said glider responsive to remote control signals for releasing said connecting means.

4. In combination with an airplane a glider, means connecting said glider to said airplane, contact means carried by said glider in contact with said connecting means, means carried by said connecting means for holding said contact means in contact with said connecting means, means in said glider responsive to any angular change of said connecting means with respect to said glider, surface control means in said glider for maneuvering the glider back to a position to correct said angular change of said connecting means operated by said responsive means, and means in said glider responsive to remote control signals for releasing said connecting means and automatically stabilizing said glider for level flight.

5. In combination with an airplane a glider,

means connecting said glider to said airplane, contact means carried by said glider in contact with said connecting means, means carried by said connecting means for holding said contact means in contact with said connecting means, means in said glider responsive to any angular change of said connecting means with respect to said glider, surface control means in said glider for correcting said angular change of said connecting means operated by said responsive means, means in said glider responsive to remote control signals for releasing said connecting means and automatically stabilizing said glider for level flight, and directional object seeking means responsive to said remote control means.

6. In combination with an aircraft, a glider, a connection from said aircraft releasably attached to said glider, automatic flight control means in said glider for operation when said glider is detached, said connection including a releasable coupling to said glider, means on said connection operated by control means in said aircraft for releasing said coupling and connection from said glider and for simultaneously turning on said automatic flight control means in said glider.

7. In combination with an aircraft, a glider, a connection from said aircraft releasably attached to said glider, automatic flight control means in said glider for operation when said glider is de-

tached, said connection including a releasable coupling to said glider, means on said connection operated by control means in aircraft for releasing said coupling and connection from said glider and for simultaneously turning on said automatic flight control means in said glider, operating devices carried by said glider having control means for their operation, and additional releasable means forming a part of said coupling for operating said control means, additional means in said aircraft for controlling said operating means in said coupling.

DELMER S. FAHRNEY.
